CONTROL MECHANISM FOR SEWING MACHINES

Jacob Brussell, New York, N. Y.

Application July 24, 1940, Serial No. 347,116

15 Claims. (Cl. 112—110)

This invention is directed to sewing machines, more particularly to mechanism associated with various parts thereof whereby adequate and valuable control of the functions of the machine may be obtained.

The present invention is directly related to the subject matter of my Patent No. 2,175,247, issued October 10, 1939, entitled "Button sewing machine," and Patent No. 2,175,248, issued October 10, 1939, entitled "Construction of button sewing machines."

It is among the objects of the present invention to provide a machine which is adapted to sew buttons and to be used for other purposes in which the functions of the machine are expanded to an extent as to allow great flexibility in use.

It is also among the objects of the present invention to provide a machine which is capable of adequate and rapid operation under widely varying conditions, including the use of the machine on buttons having two and four holes, with the use of various patterns of stitches for attaching the same to garments and the like.

It is further among the objects of the present invention to provide a construction of sewing machine which is simple, sturdy, easy to operate, which is readily adjustable by the operator of the machine, and which has a number of automatically operated parts.

The present invention as applied to a button sewing machine involves a structure wherein there is the ordinary reciprocating needle for forming stitches and a button clamp for holding the button to be sewed onto the garment. In accordance with the present invention, the needle may be caused to vibrate with each stitch transversely of its normal vertical movement. Cooperating therewith is the button clamp which may be caused to remain stationary during the vibration of the needle, or which may in itself be caused to vibrate with each stitch. The invention further provides that the clamp may vibrate in a horizontal plane during the sewing operations. Cooperating therewith, the needle may have only its normal vertical movements without any lateral movements, or the needle may be caused to shift laterally one or more times during a cycle for sewing on a button.

In the accompanying drawings, constituting a part hereof, and in which like reference characters indicate like parts,

Fig. 1 is a side elevational view of a sewing machine made in accordance with the present invention, some parts being shown diagrammati-

cally, some parts being shown in section, and other parts having been removed for the purpose of clearly illustrating the invention;

Fig. 2 is a fragmentary end view of the sewing machine head, some parts being broken away for clearness;

Fig. 3 is an enlarged fragmentary view of a portion of the mechanism controlling the movements of the needle and button clamp, shown in perspective, and some parts being broken away for clearness; and

Fig. 4 is an enlarged detail view of one of the elements supplementing the showing of Fig. 3.

The sewing machine comprises the usual bed 1, standard 2, overhanging arm 3, and sewing head 4. A horizontal shaft 5, which is the main shaft, has a crank 6 at the forward end thereof connected with a yoke 7 secured to needle bar 8 having needle 9 therein. At the rear of main shaft 5 is a crank 10 operating rod 11 which may be utilized to rotate the hook and associated mechanism located below the bed plate of the sewing machine and omitted from the drawings for clearness.

25 A driving pulley 13 is mounted on shaft 5 and is contiguous with idling pulley 12. A belt shifter 14 is secured to sliding member 15 operated by pin 16 secured to stop member 17. Said stop member is normally operated by the functioning of a latch 18 connected up by suitable linkages 19 to a controller cam 20 secured on auxiliary shaft 21, as described in Patent No. 2,175,247. A worm and gear 22 and 22' associated with shafts 5 and 21, respectively, serve to provide the 30 necessary movement of cam 20. The operation of this mechanism is to cause the stop 17 to engage a notch in collar 17' secured to shaft 5 at the proper time in order to stop the operation of the machine automatically, as described in 35 Patent No. 2,175,247 issued October 10, 1939.

A collar 23 having pins 24 mounted for oscillation in head 4, surrounds the upper part of needle bar 8. Collar 25 at the lower end of said needle bar is provided with a crank 26 operated by oscillating shaft 27. The oscillating or shifting movements of the needle bar 8 are controlled by mechanism 28, more adequately illustrated in Fig. 3.

The button clamp has a base member 29 and a pivoted body 30 terminating in button holder 31. An adjustable tension device 32 tends to hold the button holder on the bed 1 and an extension 33 on base 29 provides means for attaching the button holder to an operating mechanism. Gear 35 on shaft 5 cooperates with gear 36 carried on shaft 37, the axis of which is in

alignment with the axis of shaft 27, but is independently mounted on bearing 38. A cam 39 is secured to gear 36 and a member 40 having a follower 41 operating in cam 39 is adapted to be reciprocated thereby. It has a rectangular opening 42 within which a block 43 is adapted to slide, said block being secured onto shaft 37, the cooperation of 42 and 43 constituting guiding means for member 40. In a fork at the lower end thereof is pivoted one end of connector bar 45, the opposite end of which is pivoted in fork 46 of yoke 47. Within the opening 48 of yoke 47 is block 49 having a portion 50 closely fitting the walls of opening 48. A bolt 51 threaded into the lower end of said yoke is provided with a head 52 whereby the yoke may be adjusted so as to grip block 49 or to allow said block to remain loose. A rod 53 has one end secured in block 49, the other end being secured to operating member 54 having an opening 55 at the lower end thereof bridging bar 56 secured to extension 33 for operation of the button clamp. In an opening 57 in member 54 is fitted a bar 58 which is secured to the machine so as to allow oscillation of member 54.

In a notch 60 in member 40 is a block 61 having pivoted thereto a rectangular extension 62 which fits into slot 63 in oscillating member or link 64. Also held in slot 63 is a second block 65 into which is threaded a screw 66 adapted to cause sliding of block 65 in the slot. A set screw 65' is adapted to lock said block in adjusted position. A pin 67 extending from block 65 operates in groove 68 of stationary member 69, which is fixed by extension 70 and screws 71 to the head of the machine. At the forward end of bar 64 is a lateral extension 72 having a pin 73 fitting into plate 74 for oscillating movement.

A bar or lever 75, which is secured to plate 74 by screw 75', has a slot 76 therein and a block 77 slidably mounted for adjustment by screw 78. Set screw 77' is adapted to lock the block 77 into its adjusted positions. The rear end 79 of bar 75 is rigidly secured to shaft 27. A pin 80 is adapted to fit into notch 81 in extension 70 when the block 77 is in inoperative position. When in operative position, pin 80 cooperates with reciprocable support member 82 having an opening 83 and provided with a groove 84 for reception of said pin. A rod 85 passing through opening 83 is secured to member 82, the upper part 86 thereof being provided with plate 87. Cam rollers 88 and 88' on said plate cooperate with cam faces 89 and 89' respectively of the cam 87'. Said cam is mounted on shaft 21 and operable simultaneously with cam 20.

On the button clamp 29 is pivoted lever 91 having a set screw 92 on an extended angular arm thereof for locking the same in desired position on the button clamp. The opposite end of 91 is provided with a fork 93 which is adapted to embrace pin 94 on member 54.

Pivoted at 95 on the arm 3 is a horizontal lever 96 having a pivot 97 to which is secured vertical operating bar 98 having roller 99 at the lower end thereof. Said roller operates in angular slot 100 of plate 101, which is mounted for lateral movement. A bar 102 pivoted at 103 is mounted in the lower end 104 of member 17. A fork 105 at the opposite end embraces follower 99. An extension 106 from plate 101 terminates in a cutting knife 107. The button clamp has a vertical bar 110 secured thereto and passing into the head 4, and having an extension 111 extending through

slot 112. The free end 113 of lever 96 is positioned beneath extension 111.

The operation of the machine is as follows: When it is desired to cause the button clamp to vibrate with each stitch, the set screw 53' is loosened and rod 53 is shifted to give the desired throw of the button clamp, after which the set screw is again tightened. Bolt 51 is tightened to cause the yoke 47 to firmly grasp block 50. In this position the movement of member 40 will cause vibration of the clamp. When it is desired to allow the clamp to remain stationary, bolt 51 is loosened so as to no longer transmit motion from member 40, and end 93 of lever 91 is rotated about its pivot 115 to embrace pin 94. Screw 92 is tightened so that it contacts with the top of the button clamp to hold the same against accidental movement.

When it is desired to cause the needle bar to vibrate with each stitch, block 65 is moved so that pin 67 is engaged in groove 68. The positioning of pin 67 at various points in the length of the groove will determine the throw of the needle bar. When the pin is so engaged, reciprocation of member 40 causes reciprocation of block 62 which in turn causes oscillation of bar 64 around block 65 as a pivot. This motion is transmitted through extension 72, plate 74, bar 75 and shaft 27 to the needle bar 8. Apertured extension 116 depending from plate 74 is operatively connected with the hook mechanism (not shown) to cause the hook to be in time with the needle. When the needle bar is not to vibrate, block 65 is caused to move to the left of Fig. 3 so that it is no longer engaged with groove 68. In that case, reciprocation of block 62 merely causes oscillation of bar 64 around pivot 13 without transmitting any motion.

When it is desired to cause the needle bar to shift at predetermined intervals, pin 80 of block 75 is caused to engage with groove 84 of member 82. When pin 67 is out of groove 68 and pin 80 is held in groove 84, the motion of lever 75 is transmitted to member 116 to shift the hook mechanism. The exact positioning of the pin in the groove determines the throw of the needle bar. Since the movement of member 82 is controlled by cam faces 89 and 89', as transmitted through followers 88 and 88', at the time member 82 moves either upwardly or downwardly, bar 75 is caused to oscillate about shaft 27 due to the action of block 77 with member 82. When pin 80 is in notch 81 bar 75 is in inoperative position and there is no oscillation of shaft 27.

Briefly, the structure is adapted for use in sewing either a two hole or four hole button. In sewing a two hole button the parts should be as in Figure 3 with pin 80 out of notch 81 and with the button clamp operating connections inoperative whereby the needle will vibrate between the two holes in the button. On the other hand, the clamp operating connections may be rendered operative and the pin 67 moved out of groove 68 whereby the needle will reciprocate vertically only and the button will be moved by the clamp in sewing a two hole button.

In sewing a four hole button the clamp operating connections should be operative for moving the button for sewing through two of four holes therein. In this instance, pin 67 should be out of groove 68 and pin 80 in groove 84 whereby member 64 will oscillate about the pivotal connection between blocks 61 and 62 and by means of cam 87' having cam faces 89, 89', the needle will be moved laterally at pre-determined inter-

vals for sewing through the second two holes of a four hole button, the clamp continuing to oscillate the button for the sewing through the second pair of holes.

At the end of a stitching cycle, cam 20 causes operation of stop 17, which movement is coordinated with the shifting of the needle bar, since both cams 20 and 89 are fixed to the same shaft 21.

As the stop 17 moves upwardly, it pulls follower 99 downwardly first through the angular portion of slot 100, which shifts plate 101 to the left of Fig. 1, causing operation of knife 107 to cut the thread. Simultaneously therewith, there is downward movement of rod 98 which, through linkages 97, 95 and 113, presses upwardly on extension 111 thus raising the button clamp simultaneously with the stopping of the machine. In Fig. 1 the positions of the elements are shown after the completion of the aforesaid operation. To start the machine, chain 115 is pulled down causing follower 99 to move up and knife 107 to be retracted.

Although I have described the invention setting forth a single embodiment thereof, it is apparent that various changes and modifications in the details thereof may be made within the spirit of the invention. For instance, although the machine has been described in connection with its use for sewing buttons, it is quite obvious that at least some of the parts of the mechanism may be used with machines for other purposes. In place of the button clamp, there may be provided the ordinary presser-foot which is so linked with the remainder of the mechanism as to be automatically raised at the end of a stitching cycle. These and other changes may be made in the details of the invention without departing from the spirit thereof, the scope of the invention being defined by the claims appended hereto.

What I claim is:

1. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower cooperating with said cam, a connecting link between said follower and said lever to transmit reciprocating motion of said follower into oscillation of said needle bar, said link being pivoted at an intermediate point to a fixed support and being pivoted at its ends to said lever and follower respectively.

2. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower cooperating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot of said link being adjustable to vary the throw of said bar.

3. In a sewing machine having a rotating main shaft and stitch-forming mechanism operated thereby including a reciprocating needle bar, means for shifting said needle bar at predeter-

mined intervals comprising an oscillating shaft operatively attached to said bar and having an operating lever connected therewith, a cam rotated by said main shaft, a follower cooperating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot of said link being adjustable to vary the throw of said bar, said pivot including a stationary grooved guide, a movable block having a pin operating in said groove, and a slot in said link into which said block is movably fitted.

4. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower cooperating with said cam, a connecting link between said follower and said lever to transmit reciprocating motion of said follower into oscillation of said needle bar, said link comprising an oscillating lever, one end being pivoted to said follower and the other end being pivotally connected to one end of said first lever.

5. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said

40 follower and said lever to transmit reciprocating motion of said follower into oscillation of said needle bar, said link comprising an oscillating lever, one end being pivoted to said follower and the other end being pivotally connected to one end of said first lever, and said second lever having an adjustable intermediate pivot adapted to be rendered inoperative so that motion of said cam merely causes oscillation of said second lever about its pivotal connection with the first lever.

6. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot being adjustable to vary the throw of said bar, said pivot including a stationary grooved guide, a movable block having a pin operating in said groove, and a slot in said link into which said block is movably fitted.

7. In a sewing machine having a rotating main shaft and stitch-forming mechanism operated thereby including a reciprocating needle bar, means for shifting said needle bar at predetermined intervals comprising an oscillating shaft operatively attached to said bar and having an

operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot being adjustable to vary the throw of said bar, said pivot including a stationary grooved guide, a movable block having a pin operating in said groove, a slot in said link into which said block is movably fitted, and a screw threaded through said link and into said block for adjusting the same.

8. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot being adjustable in said fixed support to vary the range of said oscillating shaft, and means selectively operable for reciprocating said lever at predetermined intervals to shift said bar.

9. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, means for adjusting the position of said intermediate pivot to vary the throw of said link, said intermediate pivot being adjustable in said fixed support to vary the range of said oscillating shaft, and means selectively operable for reciprocating said lever at predetermined intervals to shift said bar.

10. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said support having a grooved guide, said intermediate pivot adjustably held in said guide to vary the throw of said link, said intermediate pivot being adjustable in said fixed support to vary the range of said oscillating shaft, and means

selectively operable for reciprocating said lever at predetermined intervals to shift said bar.

11. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot being adjustable in said fixed support to vary the range of said oscillating shaft, and means selectively operable for reciprocating said lever at predetermined intervals to shift said bar, including a pivot pin extending from said lever and removably held in a reciprocable support member.

12. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, said link being pivoted at an intermediate point to a fixed support and being pivoted at its ends to said lever and follower respectively, said intermediate pivot being adjustable in said fixed support to vary the range of said oscillating shaft, and means selectively operable for reciprocating said lever at predetermined intervals to shift said bar, including a pivot pin extending from said lever and removably held in a reciprocable support member.

13. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said follower and said lever to transmit reciprocating motion of said follower into oscillation of said needle bar, a button clamp, and means secured to said follower to cause vibration of said clamp including a connector bar having one end pivoted in said follower, a yoke pivoted to the other end of said connector bar, an operating rod adjustably secured to said yoke, means for clamping said rod in said yoke, and a connection between said rod and said clamp.

14. In a sewing machine having a rotating main shaft and stitch-forming mechanism operated thereby including a reciprocating needle bar, means for shifting said needle bar at predetermined intervals comprising an oscillating shaft operatively attached to said bar and having an operating lever connected therewith, a cam rotated by said main shaft, a follower co-operating with said cam, a connecting link between said

follower and said lever to transmit reciprocating motion of said follower into oscillation of said needle bar, a button clamp, and means secured to said link to cause vibration of said clamp including a connector bar having one end pivoted in said follower, a yoke pivoted to the other end of said connector bar, an operating rod adjustably secured to said yoke, means for clamping said rod in said yoke, and a connection between said rod and said clamp having means for adjusting the throw of said clamp.

15. In a sewing machine having a rotating main shaft and stitch-forming mechanism operated

thereby, a cam operated from said shaft, a stop adapted to be released by said cam for stopping the operation of said machine, a retractable member for holding fabric being sewed, a linkage connected to said stop and to said member, whereby operation of said stop causes lifting of said member and release of said stop causes lowering of said member, said linkage including a plate having an angular slot therein, a linkage pin operating in said slot, a thread cutter secured to said plate, the movement of said pin causing shifting of said cutter and then lifting of said member.

JACOB BRUSSELL.
